(57) **CLAIM**

The ornamental design for an automobile blinker light connector, as shown and described.

DESCRIPTION

FIG. 1 is a rear view of an automobile blinker light connector;

FIG. 2 is a perspective view thereof;

FIG. 3 is a right side view thereof;

FIG. 4 is a left side view thereof;

FIG. 5 is a plan view thereof; and,

FIG. 6 is an opposite inverted plan view thereof.

The front view contains no ornamentality and is omitted. The broken line showing is for illustrative purposes only and forms no part of the claimed design.
